Primary Examiner — Ian Simmons*Assistant Examiner* — Shannon Morgan(74) *Attorney, Agent, or Firm* — Kaplan Breyer Schwarz & Ottesen, LLP; Harry K. Ahn(57) **CLAIM**

The ornamental design for a handheld slicer with hand guard, as shown and described herein.

DESCRIPTION

FIG. 1 is a top, right side perspective view of a handheld slicer with hand guard showing our new design;

FIG. 2 is a rear elevational view thereof;

FIG. 3 is a right side elevational view thereof;

FIG. 4 is a top plan view thereof;

FIG. 5 is a left side elevational view thereof; and,

FIG. 6 is a front elevational view thereof.

The broken lines shown in FIGS. 1-6 represent portions of the handheld slicer with hand guard that form no part of the claimed design.
